UNITED STATES PATENT OFFICE.

JOHN STEMBER, OF NEW YORK, N. Y.

DESIGN FOR A BELT.

SPECIFICATION forming part of Design No. 33,620, dated November 27, 1900.

Application filed October 24, 1900. Serial No. 34,218. Term of patent 3½ years.

To all whom it may concern:

Be it known that I, JOHN STEMBER, a citizen of the United States, and a resident of the city of New York, borough of Manhattan, in the county and State of New York, have invented and produced a new and original Design for a Belt, of which the following is a specification, reference being had to the accompanying drawing, forming a part thereof, in which the drawing represents a perspective view of a belt embodying the features of my design.

The leading feature of the design consists in sections A and B of the belt, united at the back by an ornamental connection C, at which connection a portion of one section is passed through the other, so that the terminal of one section rests upon the outer face of the adjacent section.

A minor feature of the design consists in pointing the ends of the sections of the belt and bringing the ends of the sections together to form a diamond ornament at the back of the belt.

Having thus described my invention, I claim as new and desire to secure by Letters Patent—

The design for a belt herein shown and described.

In testimony whereof I have signed my name to this specification in the presence of two subscribing witnesses.

JOHN STEMBER.

Witnesses:

BEN GORDON,
A. V. CLARK.
